UNITED STATES PATENT OFFICE.

CHARLES ROBERT BANGS, OF NEW YORK, N. Y.

IGNITING DEVICE FOR EXPLOSIVE-ENGINES.

1,189,906.

Specification of Letters Patent. Patented July 4, 1916.

Application filed February 6, 1913. Serial No. 746,545.

To all whom it may concern:

Be it known that I, CHARLES R. BANGS, of New York, in the county of New York, and in the State of New York, have invented a certain new and useful Improvement 5 in Igniting Devices for Explosive-Engines, and do hereby declare that the following is a full, clear, and exact description thereof.

10 The object of my invention has been to provide an igniting device for explosive engines which shall be exceedingly simple in construction and operation, and shall efficiently ignite the combustion mixture, and 15 particularly one which can be operated by the compression of the gases and without an electric or other sparking device, and one which need not increase the difficulty of cranking the engine so greatly as to require an automatic starting device, and to 20 such ends my invention consists in the igniting device for explosive engines hereinafter specified.

In the accompanying drawings—the figure 25 is a cross-sectional view of a portion of an engine cylinder (with its piston) and having a form of my starting device applied thereto.

My invention is capable of embodiment in 30 many different forms, and while the embodiment which I shall illustrate and describe is the best embodiment known to me, it is to be regarded as typical only of many possible embodiments, and my invention is 35 not to be confined thereto. In the illustrated embodiment I have shown a cylinder 1 and piston 2 of an explosive engine, the piston being moved by the piston rod 3. On the cylinder head 4 I have provided an 40 ignition cylinder 5 which, in the present instance, is cast in one piece with the engine cylinder. I desire to compress a portion of the explosive mixture in the ignition cylinder to a pressure at which the charge will 45 automatically ignite and communicate the combustion thus created to the main charge in the engine. For this purpose I provide a piston 6 to be forced into the ignition cylinder, the piston preferably being carried 50 by the moving parts of the engine proper, as by the piston rod. I also desire to afford communication between the compressed gases in the ignition cylinder and the main charge in the engine cylinder, after 55 the ignition in the ignition cylinder, and to accomplish these two purposes I believe the

following construction is efficient and convenient. The piston 6 is formed on or carried by the free end of a tube 7, which latter is screwed upon a stud 8 formed on 60 the piston rod. The piston is provided with a hole 9 through which the combustion may travel to the interior of the tube 7, and the latter is provided with holes 10 at such a distance from the piston 6 that when the 65 latter has entered the ignition cylinder to the maximum extent, the openings 10 shall be at least partially without the ignition cylinder and thus communication will be afforded from the ignited portion of the 70 gases through the hole 9 and by way of the interior of the tube 7 and through the openings 10 into the main cylinder. I also preferably provide openings 11 near the upper end of the tube for a purpose to be described. 75

In the operation of my device in the form illustrated, the ignition cylinder and its piston are preferably made of sufficiently small diameter so that the compression of gases in said cylinder may be effected by hand (in the ordinary automobile engine) and not necessarily require an automatic starter. The opening 9 is made sufficiently small so that, at the speed which it is possible to give the piston 6, the gases in the ignition cylinder will be sufficiently slow in escaping through the opening 9 to still afford the desired degree of compression to ignite the gases from the compression alone. On starting the engine, the down stroke of the piston 2 will draw in the explosive charge from any source (not shown). Upon the up stroke of the piston 2, the piston 6 will be driven into the ignition cylinder and the charge compressed therein. The clearance in the ignition cylinder is made smaller than that in the engine cylinder so that when the gases in the engine cylinder are only compressed to the ordinary degree, such, for instance, as when they are to be ignited electrically, the gases in the ignition cylinder will be compressed to a degree at which the compression alone will ignite them. The gases in the ignition cylinder being ignited, the ignition will travel through the opening 9 and down the interior of the tube 7 and will reach the main charge in the engine cylinder through the openings 10. I preferably provide the openings 11 in order to permit the burned gases in the tube 7 to more readily escape when the tube is wholly

within the main cylinder, and thus prepare the way for a portion of the fresh charge to enter the said tube. As the tube 7 is screwed on the lug of the piston rod, its

5 piston can be adjusted up and down by screwing the tube up and down on the said lug and thus the clearance in the ignition cylinder may be regulated.

I claim:

10 1. An ignition device for explosive engines comprising an engine cylinder and piston, an ignition cylinder opening directly into said engine cylinder, a piston therefor, and means affording constant communication between the closed end of said ignition cylinder and said engine cylinder.

15 2. An ignition device for explosion engines comprising an engine cylinder and piston, an ignition cylinder and piston, and 75 means for operating the same, said ignition cylinder and piston being provided with a passage communicating with the main cylinder to permit ignition to travel thereto.

20 3. An ignition device for explosion engines comprising an engine cylinder and piston, an ignition cylinder and piston, and 80 means for operating the same, said ignition piston being provided with a passage therethrough.

25 4. In an ignition device for explosion engines, the combination of an engine cylinder and piston, an ignition cylinder and piston, the latter having an opening therethrough, and a support for the ignition piston mounted 85 on the engine piston or piston rod.

30 5. In an ignition device for explosion engines, the combination of an engine cylinder and piston, an ignition cylinder and piston, the latter having an opening therethrough, 90 and a support for the ignition piston mounted on the engine piston or piston rod, said support being of smaller cross-section than said ignition piston.

35 6. In an ignition device for explosive engines, the combination of an engine cylinder and piston, an ignition cylinder, a piston for the latter comprising a disk having an opening therethrough, and a tube supporting 95 said disk on the engine piston or piston rod, said tube having openings through its walls near the piston end thereof.

40 7. In an ignition device for explosive engines, the combination of an engine cylinder and piston, an ignition cylinder, a piston 105 for the latter comprising a disk having an opening therethrough and a tube supporting said disk on the engine piston or piston rod, said tube having openings through its walls near the piston end thereof, said tube 110 being so mounted on said piston or piston rod that the clearance in the ignition cylinder may be adjusted.

45 8. An ignition device for explosive engines, comprising an engine cylinder and piston, an ignition cylinder and piston and 115

means for operating the same, said ignition piston being provided with a passage therethrough, and means for adjusting the clearance in the ignition cylinder.

9. An ignition device for explosive engines, comprising an engine cylinder and piston, an ignition cylinder and piston and 75 means for operating the same, said ignition piston being provided with a passage therethrough, and means for adjusting the clearance in the ignition cylinder, said means comprising means for adjusting the piston relative to the parts by which it is operated.

10. In an ignition device for explosive engines, the combination of an engine cylinder and piston, an ignition cylinder opening directly into said engine cylinder and comprising immovable parts, and a piston adapted to enter said ignition cylinder. 80

11. In an ignition device for explosive engines, the combination of an engine cylinder and piston, an ignition cylinder, and a piston adapted to enter said last-mentioned cylinder and provided with an opening sufficiently small compared with the displacement of said ignition piston to cause compression of the entrapped gases to the ignition point. 85

12. In an ignition device for explosive engines, means to impart motion by utilizing 90 explosive gases comprising a cylinder, a piston, and a piston rod; an ignition device comprising a piston with an opening therethrough, and a cylinder; said ignition device being mounted on said motion-imparting 95 means. 100

13. An ignition device for explosive engines comprising an engine cylinder and piston, an ignition cylinder having the end opposite its compression end opening directly into said engine cylinder, a piston therefor, and means affording constant communication between the closed end of said ignition cylinder and said engine cylinder. 105

14. In an ignition device for explosive engines, the combination of an engine cylinder and piston, an ignition cylinder having the end opposite its compression end opening directly into said engine cylinder and comprising immovable parts, and a piston 110 adapted to enter said ignition cylinder.

15. An ignition device for explosive engines comprising an engine cylinder and piston, an ignition cylinder communicating with said engine cylinder by an opening in 115 said engine cylinder as large as said ignition cylinder, a piston for said ignition cylinder, and means affording constant communication between the closed end of said ignition cylinder and said engine cylinder. 120

16. In an ignition device for explosive engines, the combination of an engine cylinder and piston, an ignition cylinder communicating with said engine cylinder by an opening in 125 said engine cylinder as large as said 130

ignition cylinder and comprising immovable parts, and a piston adapted to enter said ignition cylinder.

17. In an ignition device for explosive engines, the combination with an engine cylinder and piston, of an ignition device mounted on said engine cylinder and piston and comprising an ignition cylinder and piston provided with means to afford constant communication between the closed end of said ignition cylinder and said engine cylinder.

18. In an ignition device for explosive engines, the combination with an engine cylinder and piston, of an explosive cylinder and piston one of which is mounted on said engine cylinder and the other of which is mounted on said engine piston and one of which is provided with an opening to afford

constant communication between the closed end of said ignition cylinder and said engine cylinder.

19. In an ignition device for explosive engines, the combination with an engine cylinder and piston, of an explosive cylinder and piston one of which is mounted on said engine cylinder, and the other of which is mounted on said engine piston and is provided with means to afford constant communication between the closed end of said ignition cylinder and said engine cylinder.

In testimony that I claim the foregoing I have hereunto set my hand.

CHARLES ROBERT BANGS.
